CLAIM

The ornamental design for a buoyant belt, as shown.

DESCRIPTION

FIG. 1 is a perspective view of the top, front, and right side of a buoyant belt showing my new design;

FIG. 2 is a front elevation view of my new design;

FIG. 3 is a side elevation view taken from the right side of FIG. 2;

FIG. 4 is a back elevation view;

FIG. 5 is a top plan view of my design;

FIG. 6 is a bottom plan view of my design; and

FIG. 7 is a side elevation view of the left side of FIG. 2.

FIG. 1

FIG. 3

FIG. 2

FIG. 4

FIG. 5

FIG. 6

FIG. 7
